CLAIM

The ornamental design for a rear support for a rack for a vehicle, as shown and described.

DESCRIPTION

FIG. 1 is a perspective view of a rear support for a rack for a vehicle;

FIG. 2 is a right elevation view of the rear support;

FIG. 3 is a left elevation view of the rear support;

FIG. 4 is a front elevation view of the rear support;

FIG. 5 is a rear elevation view of the rear support;

FIG. 6 is a top plan view of the rear support; and,

FIG. 7 is a bottom plan view of the rear support.

The broken lines are included for the purpose of illustrating environment and form no part of the claimed design.

1 Claim, 6 Drawing Sheets
